INVENTOR

W. H. Elliot.

UNITED STATES PATENT OFFICE.

WILLIAM H. ELLIOT, OF NEW YORK, N. Y.

MAGAZINE FIRE-ARM.

SPECIFICATION forming part of Letters Patent No. 293,315, dated February 12, 1884.

Application filed December 3, 1883. (No model.)

To all whom it may concern.

Be it known that I, W. H. ELLIOT, a citizen of the United States, residing at New York, in the county of New York and State of New York, have invented a new and useful Improvement in Magazine Fire-Arms, of which the following is a specification.

The object and nature of my invention may be described as follows:

10 The object of my invention is to provide a cheaper and safer magazine fire-arm than any now in use; and the nature of my invention consists in the use of certain appliances and methods, which are fully set forth in the following specification and claims.

Figure 1 is a vertical longitudinal section of my improved arm, showing some of the limb-work in elevation. Fig. 2 is an elevation of a portion of the limb-work, showing the position of the same when the chamber is open. Fig. 3 is a plan of the brace, showing smaller parts attached thereto. Fig. 4 is a front elevation of the bolt. Fig. 5 is a vertical cross-section of the arm through the operating-handle. Fig. 6 is a vertical section of the brace, showing the levers for starting it from the recoil-shoulders. Fig. 7 is a plan of the carrier.

My invention is applicable particularly to 30 that kind of arm which has a tubular magazine arranged under the barrel, and a bolt or breech-block which moves in a line with the barrel to close the chamber. It is also applicable to arms having detachable magazines.

35 The receiver *a* has the barrel *b* screwed into its forward end in the usual way. It also supports the guard-strap *g*. This latter device has upon its forward end an upward-projecting portion, *g'*, which is bored through to receive and support the rear end of the magazine-tube *t*. The upward projection, *g'*, is provided with two lateral projections—one upon each side—which rest against the forward end 40 of the receiver and serve as recoil-shoulders, as shown in my patent of September 18, 1883. The breech-block is moved back and forth, locked, and the carrier operated by means substantially such as are shown in my patent

of May 29, 1883, to both of which patents I 50 make special reference. The bolt *c* has a dependent portion, *c'*, at its forward end, to which the brace *d* is pivoted at *c''*. This brace, when the arm is closed, rests at its rear end upon the recoil or locking shoulders *g''*, which 55 may be formed upon the guard-strap or upon the receiver, as shown in said patents. The upper edges of the hollow handle *n* run in and are supported by parallel grooves *b'*, cut in the barrel above and independent of the magazine-tube *t* and guard-strap, as shown in Figs. 1 and 5. This handle is provided with a connecting-strap, *h*, which extends backward into the receiver, and is at its rear end connected with the breech-block by means of the 60 downward-projecting arm or link of the brace *d''*, said arm being pivoted at its lower end to the rear end of the connecting-strap at *h'*, and is also connected at its upper end, through the brace *d*, with the breech-block at 65 *c''*, whereby the rear end of said connecting-strap is held to a substantially parallel movement by the breech-block, independent of the guard-strap as a guide or support. These last- 70 mentioned features are among the most important of my invention. The grooves or guides for the handle being in the barrel or above the magazine-tube, they are in almost a direct line with the movement of the breech-block. There is, therefore, less tendency to 75 lateral pressure and consequent friction than there would be if the guides for the handle were in the guard-strap, as shown in said 80 patents.

By providing guides for the handle above 85 and independent of both the magazine-tube and guard-strap, the construction of the guard-strap becomes much less expensive, as the long grooves for the connecting-strap and the extension of the guard-strap forward of the receiver are both dispensed with. In addition to these advantages there is still further the advantage of having the magazine-tube independent of all of the moving parts of the breech mechanism, as in that case the breech mechanism can be assembled and its movements 90 tested without having the magazine in its place, and the magazine may be taken out for 95

repairs or cleaning without disturbing the rest of the arm; and while out the arm may be used as a single breech-loader as practically as with the magazine in place, which is sometimes very desirable. The carrier s is pivoted near its rear end, and is provided with an upward projection, s' , in rear of its pivot, whereby its forward end is raised by the brace during its backward movement, as shown in Fig. 2, and is depressed to receive a cartridge from the magazine by the inclined surfaces e and e' on the forward end of the breech-block. The carrier is slotted or bifurcated, as shown in Fig. 7, the two sides being connected together at the forward end by the bar s'' , and may be similarly connected at the rear end, if so desired. As the arm is being closed, the surface e , moving along upon the carrier, partly depresses it, when the surface e' , coming against the bar s'' , forces the carrier down to the position shown in Fig. 1.

By reference to Fig. 1 it may be seen that the surface of the rear end of the brace d'' is cut eccentric to the axis of that device, and concentric with the center i considerably above the axis of the brace; also, that the shoulders d' on each side of the brace, being struck from the same center, are parallel and equally eccentric to the said axis. The recoil-shoulders g'' are rigidly supported by the receiver, and have a form corresponding with that of the end of the brace d'' , so that the downward movement of the rear end of the brace, acting against the recoil-shoulders, carries the bolt forward with great force, to complete the insertion of the cartridge. The pins or shoulders m project rigidly from the inner surface of the receiver, and rest against the eccentric surfaces d' , so that when the brace is raised in the act of opening the chamber, the pins m , acting upon the eccentric shoulders d' , cam the bolt back with equal force to start a shell that sticks in the chamber.

By reference to Figs. 1, 3, and 6 it may be seen that the arm d'' of the brace is pivoted to that device at c'' , and has a limited movement in relation to it, without affecting its function of moving the bolt; also, that the said arm has a projection backward at its upper end, which rests against the under side of the rear end of the lever o , which is also pivoted to the brace at o' , and rests at its rear end upon the top of the recoil-shoulders g'' . When in the manipulation of the arm the lower end of the arm d'' is carried backward, it acts as a lever to raise the forward end of the lever o , which, in turn, acting upon the top of the recoil-shoulders, raises the rear end of the brace, and so releases it from the pressure of a swelled cartridge-head.

In Figs. 1 and 2 the hammer r is represented as being constructed with a long curved projection, r' , extending forward over the rear end of the carrier when the hammer is down and resting upon the rear end of the bolt, and

also forms a recess, r'' , for the reception of the central portion of the rear end of the brace when the bolt is back and the chamber open. By this construction of the hammer the rear end of the receiver is kept at all times closed, and room is provided for the carrier and brace without increasing the length of the receiver for that purpose. 70

Having described my invention, what I desire to have secured to me by Letters Patent 75 of the United States is—

1. The combination, in a magazine fire-arm, of the longitudinally-reciprocating strap h , pivotally connected at its rear end to the arm d'' of the brace of the breech-block, and having at its forward end the handle n , with inwardly-projecting arms or edges, taking with the grooves or guides in the barrel above and independent of both the magazine-tube and the guard-strap, whereby the handle is supported and guided independently of said tube and guard-strap, and the rear end of said connecting-strap is guided by the breech-block, substantially as shown and described. 80 85

2. In a magazine fire-arm, the construction 90 and combination of devices substantially as follows: a breech-block for closing the chamber, movable in a line with the barrel, actuated by a longitudinally-reciprocating handle, n , arranged forward of the receiver, through 95 a suitable connection therewith, and having upon its forward end the inclined surfaces or cams e and e' , a bifurcated or slotted carrier pivoted at its rear end and provided with bar s'' , upon which said surfaces act, whereby the 100 carrier is depressed from its highest to its lowest position by the said inclined surfaces during the forward movement of the breech-block, substantially as specified.

3. In a magazine fire-arm, a breech-block, 105 movable in a line with the barrel, bearing the pivotally-connected brace, and having the eccentric bearing-surfaces d'' , for forcing the cartridge into the chamber, and d' , for starting the cartridge-shell out of the chamber, in 110 combination with the receiver having the stationary shoulders g'' and m rigidly fastened thereto, whereby the cartridge is forced home in the chamber, and the shell is started out of the chamber by the alternate raising and lowering of the brace, substantially as shown and described. 115

4. In a magazine fire-arm, a breech-block provided with a brace for resisting the recoil of the charge, which brace abuts upon suitable 120 recoil-shoulders that are formed eccentric to the axis of the brace and are supported by the receiver, and in combination therewith the two levers d'' and o , both being pivoted to the brace and acted upon by the devices that give 125 movement to the breech mechanism, to displace the brace from the recoil-shoulders, substantially as specified.

5. In a magazine fire-arm, a hammer having the curved projection r' extending for 130

ward from the face of the hammer under the rear end of the bolt, and the recess r'' under said projection, in combination with the carrier s and brace d , the parts being arranged in such relation to each other that during the manipulation of the arm the rear end of the carrier occupies the recess r'' when the arm is closed and the hammer down, the rear

end of the brace occupies said recess when the arm is open, and the rear end of the receiver is kept all the time closed, substantially as shown and described.
